205,643

MOTOR-PROPELLED UNDERWATER BREATHING AND DIVING APPARATUS

John Gary Strader, St. Louis, Mo., assignor to The Gary
Aqua-Peller Corporation, New York, N.Y.

Filed Nov. 24, 1965, Ser. No. 88,203

Term of patent 14 years

(Cl. D71—1)

FIG. 1

FIG. 2

FIG. 3

FIG. 5

FIG. 4

FIG. 1 is a front view of the motor-propelled underwater breathing and diving apparatus;

FIG. 2 is a side view;

FIG. 3 is a top view;

FIG. 4 is a bottom view; and

FIG. 5 is a back view.

The side which is not shown is identical to the view shown in FIG. 2. The portions shown in broken lines are included for illustrative purposes only.

I claim:

The ornamental design for a motor-propelled underwater breathing and diving apparatus, as shown and described.
